LOCOMOTIVE FRONT END

William F. Mitchell, St. Paul, Minn., assignor
to Locomotive Firebox Company, Chicago, Ill.,
a corporation of Delaware

Application May 14, 1932. Serial No. 611,428

16 Claims. (Cl. 230—97)

This invention relates to improvements in locomotive front ends and it consists of the matters hereinafter described and more particularly set forth in the appended claims.

5 The primary object of the invention is to provide a front end construction of this kind wherein the live cinders from the flues entering the smoke box are caused to travel in a somewhat circuitous and whirling path whereby they are broken up, extinguished and cooled before they 10 are discharged through the stack.

Another object of the invention is to provide in the smoke box, a transversely extending drum having end openings at the front so arranged 15 in connection with a coacting cone as to produce a whirling action to the incoming cinders and products of combustion, wherein the heavier particles thereof are centrifugally separated out to fall to the more quiet area at the bottom of the 20 drum for easy removal.

A further object of the invention is to provide a construction of this kind, which may be readily installed in locomotives already in service with but little lay-up time and which in no manner interferes with the use of the usual spark screens, 25 superheater headers or other devices found in the smoke boxes of modern locomotives.

These objects of the invention as well as others, together with the many advantages thereof 30 will more fully appear as I proceed with my specification.

In the drawing:—

Fig. 1 is a longitudinal vertical sectional view 35 through a locomotive front end embodying my invention.

Fig. 2 is a transverse vertical sectional view through the same as taken on the line 2—2 of Fig. 1.

Referring now in detail to that embodiment 40 of the invention illustrated in the accompanying drawing, 1 indicates as a whole the tubular body of the smoke box shell, 2 indicates the front flue sheet forming the rear wall of the smoke box and 3 indicates the smoke box front 45 having the usual door 4 associated therewith. 5 indicates the flues fixed at their front ends in the flue sheet 2 to open in the usual manner into the smoke box.

6 indicates the barrel of the stack having a 50 flanged base 7 secured to the top of the body of the smoke box shell in any desired manner about the usual opening therein, down through which the inside extension 8 of the stack projects. Preferably this inside extension has a 55 bottom radial flange 9 to which a similar flange

10 of a petticoat pipe 11 is fixed. 12 indicates the exhaust pipe, rising from the bottom of the smoke box shell, in substantially axial alignment with the stack. Preferably the top end of said pipe is radially flanged as at 13 to receive the like flange 14 of an exhaust nozzle or tip 15.

In said smoke box shell is a horizontally disposed cylindrical casing 16 with its axis arranged transversely of said shell. Centrally at the top 60 of said casing, is an upwardly extending tubular neck 17 that encloses the top end part of the petticoat pipe, the remainder of said petticoat pipe being within said casing.

Preferably this neck has an inturned radial 70 flange 18 that is disposed between the like flanges 9 and 10 of the stack extension and petticoat pipe and is secured in place by the same bolts 19 that secure said flanges together. This tubular casing 16 is supported at the bottom by legs 20—20 75 which are fixed at their bottom end to the smoke box shell and are provided at their top ends with curved arms 21 forming saddles, secured to the bottom of said casing.

The casing has end walls 22—22 and the space 80 between said end walls and said shell as well as those three cornered spaces between said shell, the top of the casing and the smoke stack extension are closed off by baffle plates 23 and 24 respectively, secured in place in any suitable manner. 85

Extending inwardly from each end wall of the casing and coaxially therewith is an apiced cone 25, of an axial length to terminate short of the planes of the opposite sides of the neck 17 and the 90 purpose of which will later appear.

At the front of the casing at each side thereof is a rectangular inlet opening 26 the top of which is overhung by a hood or vizor 27. Extending upwardly and inwardly from the bottom of said inlet opening is a deflector plate 28 that terminates at its top edge on the circle of the base of the cone and in the plane of the axis of the cone as best shown in Fig. 1.

At the bottom of the casing, concentric with 100 the nozzle is located a short upright cylindrical cinder ring or catcher 29 the flat bottom wall of which is disposed and clamped between the flanges 13 and 14 of the exhaust pipe and its nozzle or tip. At the front of said ring or catcher 105 which is preferably of a diameter corresponding to the casing neck 17 and outside the casing is a door 30 for the removal of such cinders or the like as may accumulate therein.

As the products of combustion enter the smoke 110

- box from the flues 5, they are forced to take a downward path because of the baffles 23—24 closing off the space about the top and ends of the casing. Thus said products, sweep downwardly and laterally to divide substantially into two streams each entering an inlet opening 26, the hood 27 associated with each opening directing said products thereto.
- As said products enter said openings they are directed by the deflectors 28 into engagement against the associated cone 25 so that a whirling centrifugal action is induced to each stream. This acts to direct the heavier particles radially outward so that they are forced to take a longer and more circuitous path before they enter the bottom end of the petticoat pipe. Thus the glowing live cinders are not only broken up, but are cooled and extinguished to pass out the stack.
- By reason of the cones, the lighter products of combustion are deflected toward the apex thereof and from there, enter the bottom of the petticoat pipe under the forced draft action of the nozzle. Thus by reason of the construction described, the products of combustion are caused to take on a whirling centrifugal action which breaks up and extinguishes the heavier live particles or cinders before they enter the petticoat pipe so that they are in such a condition when they leave the stack as will make it impossible to start fires along the right of way. Such particles as are too heavy to pass out the stack are caught in the cinder ring and may be easily removed through the front thereof.
- The structure described, is simple to produce and may be installed in locomotives already in service with but a small lay-up time and may also be readily installed in new locomotives in the course of their assembly. There are no moving parts to get out of order and nothing to manipulate so that long periods of usefulness without expense is possible.
- While in describing the invention, I have referred in detail to the form and construction of the various parts thereof, the same is to be considered merely as illustrative of but one embodiment of the invention, so that I do not wish to be limited thereto except as may be specifically set forth in the appended claims.
- I claim as my invention:
1. A locomotive front end embodying therein a smoke box defined at one end by a flue sheet, a smoke stack having a stack extension in the smoke box, an exhaust nozzle in the smoke box associated with said stack extension, means in said smoke box forming a chamber surrounding said stack extension, there being an opening provided for the admission of the products of combustion into said chamber, said parts being so formed and positioned as to cause said products of combustion to take a substantially circular path about a transversely disposed horizontal axis arranged between said flue sheet and said opening.
  2. A locomotive front end embodying therein a smoke box defined at one end by a flue sheet, a smoke stack having a stack extension in the smoke box, an exhaust nozzle in the smoke box associated with said stack extension, means in said smoke box forming a chamber surrounding said stack extension, there being an opening provided for the admission of the products of combustion into said chamber, said parts being so formed and positioned as to cause said products of combustion to take a substantially circum-

lar path about a transversely disposed horizontal axis and under the bottom of said means forming said chamber in their passage between said flue sheet and said opening.

3. A locomotive front end embodying therein a smoke box shell having a smoke stack at the top and an exhaust nozzle at the bottom, a transversely disposed casing in said shell and into which parts of said stack and nozzle extend, there being an inlet opening in said casing at the front thereof and means in said casing so arranged with respect to said inlet opening as to impart a whirling action to the products of combustion entering the same, about a horizontal axis arranged transversely of the smoke box shell to separate out the heavier particles thereof and to direct the lighter particles in toward the plane of said stack and nozzle.

4. A locomotive front end embodying therein a smoke box shell having a smoke stack at the top and an exhaust nozzle at the bottom, a transversely disposed casing in said shell and into which parts of said stack and nozzle extend, means providing an inlet opening in the front of said casing with a hood at the top of the same, and means providing a cone in said casing so positioned with respect to said inlet opening as to provide a whirling action to the products of combustion entering said inlet opening to cause a separation between the lighter and heavier particles of said products of combustion.

5. A locomotive front end embodying therein a smoke box shell having a smoke stack at the top and an exhaust nozzle at the bottom, a transversely disposed casing in said shell and into which parts of said stack and nozzle extend, means providing an inlet opening in the front of said casing with a hood at the top, means providing a cone in said casing so positioned with respect to said opening as to impart a whirling action to the products of combustion entering the same and a deflector plate in said casing extending upwardly and inwardly from the bottom of said opening to direct the incoming products of combustion against said cone.

6. A locomotive boiler embodying therein a smoke box shell having a smoke stack at the top and an exhaust nozzle at the bottom, means providing a transverse casing in said shell with a neck secured to a part of the stack, means for supporting said casing from said shell, which has an opening at each end at the front of the casing, a hood above each opening, a cone supported in said casing coaxially therewith so as to be engaged by the products of combustion entering said openings and means providing baffles between the ends and top of said casing and said smoke box shell.

7. A locomotive boiler embodying therein a smoke box shell having a smoke stack at the top and an exhaust nozzle at the bottom, means providing a transverse casing in said shell with a neck secured to a part of the stack, means for supporting said casing from said shell which has an opening at each end at the front of the casing, a hood above each opening, a cone supported in said casing coaxially therewith so as to be engaged by the products of combustion entering said openings, a deflector extending upwardly and inwardly from the bottom of each inlet opening and terminating short of the associated cone and means providing baffles between the ends and top of the casing and the smoke box shell.

8. A locomotive boiler embodying therein a

- smoke box shell having a smoke stack at the top and an exhaust nozzle at the bottom, means providing a transverse casing in said shell with a neck secured to a part of the stack, means for supporting said casing from said shell which has an opening at each end at the front of the casing, a hood above each opening, a cone supported in said casing coaxially therewith so as to be engaged by the products of combustion entering said openings, a cinder ring in said casing about said nozzle and means providing a baffle between the ends of the top of said casing and said smoke box shell. 80
9. In a locomotive front end, a cylindrical casing adapted to be positioned transversely in a smoke box shell and having ends, means providing an opening at the top of said shell midway between said ends, there being openings in the front of the casing near each end, a hood at the top of each opening in the front of the casing, a cone extending inwardly from each end of the casing and a deflector plate extending upwardly and inwardly from the bottom of each opening in the front of the casing. 85
10. A locomotive front end embodying therein a smoke box shell, a smoke stack at the top thereof having an extension in the shell, a nozzle at the bottom of the shell, means providing a chamber in the smoke box shell with which chamber the stack extension and nozzle communicate, said means being formed at the front with laterally spaced inlet openings one arranged on each side of the perpendicular axis of the stack extension, said means and inlet openings 100 coaxing in causing the products of combustion entering said openings to take substantially circular paths about a horizontal axis extending transversely of the shell. 105
11. A locomotive front end embodying therein a smoke box shell, a smoke stack at the top thereof having an extension in the shell, a nozzle at the bottom of the shell, means providing a chamber in the smoke box shell with which chamber the stack extension and nozzle communicate, said means being formed at the front end with laterally spaced inlet openings one on each side of the perpendicular axis of the stack extension, said means and inlet openings coaxing in causing the products of combustion entering said openings to take substantially circular paths about a horizontal axis extending transversely of the shell, and means in said chamber providing means for directing those parts of the products of combustion near the axis of said paths, in toward the perpendicular plane of the stack extension. 115
12. A locomotive front end embodying therein a smoke box shell, a smoke stack at the top thereof having an extension on the shell, a nozzle at the bottom of the shell, means providing a casing in the shell having a horizontal axis disposed transversely of the shell and into which the stack extension and nozzle extend, said casing having laterally separated inlet openings at the front thereof, one spaced to each side of the axis of the stack extension, a deflector associated with one of the horizontal edges of each opening for causing the entering products of combustion to take a circular path about the horizontal axis of the casing, a hood associated with the top part of each opening and means for closing off the space between the ends and top of the casing and adjacent parts of the smoke box shell. 120
13. A locomotive front end embodying therein a smoke box shell, a smoke stack at the top thereof having an extension on the shell, a nozzle at the bottom of the shell, means providing a casing in the shell having a horizontal axis disposed transversely of the shell and into which the stack extension and nozzle extend, said casing having laterally separated inlet openings at the front thereof, one spaced to each side of the axis of the stack extension, a deflector associated with the bottom part of each opening for causing the entering products of combustion to take a circular path about the horizontal axis of the casing, a hood associated with the top part of each opening and means for closing off the space between the ends and top of the casing and adjacent parts of the smoke box shell. 125
14. A locomotive front end embodying therein a smoke box shell, a smoke stack at the top thereof having an extension in the shell, a nozzle at the bottom of the shell, means providing a casing in the shell having a horizontal axis disposed transversely of the shell and into which the stack extension and nozzle extend, said casing having laterally separated inlet openings at the front thereof, one spaced to each side of the axis of the stack extension, a deflector associated with one of the horizontal edges of each opening for causing the entering products of combustion to take a circular path about the horizontal axis of the casing, and means carried by each end of the casing and each associated with an inlet opening for directing those parts of the products of combustion near the axis of said paths, in toward the plane of the stack extensions. 130
15. A locomotive front end embodying therein a smoke box shell having a smoke stack with an extension therein, means providing a chamber in the smoke box surrounding the bottom end of the stack extension, said means being formed to provide a front inlet opening for said chamber, said chamber providing means and inlet opening being so formed as to coax in causing the products of combustion entering said inlet opening to take a substantially circular path about a horizontal axis arranged transversely of the smoke box shell and an exhaust nozzle in the bottom of the smoke box and opening through the bottom of said chamber providing means in line with said smoke stack. 135
16. A locomotive front end embodying therein a smoke box shell having a smoke stack with an extension therein, an associated exhaust nozzle and means providing a chamber in the smoke box surrounding the bottom end of the stack extension and the top end of the exhaust nozzle, said means being formed to provide a front inlet for said chamber, said chamber providing means and said inlet opening being so formed as to coax in causing the products of combustion entering said inlet opening to take a substantially circular path about a horizontal axis arranged transversely of the smoke box shell, and means associated with said inlet opening for directing the products of combustion inlet said chamber at a point above the bottom of the stack after passing beneath the bottom of said chamber providing means. 140
